UNITED STATES PATENT OFFICE.

THOMAS FRANCIS TIERNEY, OF NEW YORK, N. Y.

DESIGN FOR A SUPPORTING STANDARD AND FRAME FOR CHURN-OPERATING MECHANISM.

SPECIFICATION forming part of Design No. 32,759, dated May 29, 1900.

Application filed May 2, 1900. Serial No. 15,280. Term of patent 7 years.

To all whom it may concern:

Be it known that I, THOMAS FRANCIS TIERNEY, a citizen of the United States of America, residing in New York city, in the county and State of New York, have invented and produced a new and original Design for a Supporting Standard and Frame for Churn-Operating Mechanism, of which the following is a specification, reference being had to the accompanying drawings, forming a part hereof, and wherein—

Figure 1 is a front view in elevation, showing my new design. Fig. 2 is a plan view of the base of the standard and cross-section thereof, taken on the line 2 2 of Fig. 1. Fig. 3 is a side view in elevation of my new design.

As shown in the drawings, the leading or material feature of my design consists of a flat base *a*, segmental in exterior contour, with the ends of the segment rounded into the straight boundary of the segment, as indicated at *b b* in Fig. 2 of the drawings. From the base is produced and rises a vertical standard *c*, formed of intersecting flanges arranged at right angles to each other and curved inward at the bases. From the top of the standard thus formed a frame *d* is vertically ex-

tended, consisting of a curved base and vertically-aligning side standards *e e*, having central vertical flanges *e' e'* on their outer faces, and upper and lower circular sleeves *f f'*, formed with bearing-apertures, in which may be journaled such shafts as are requisite. The top of the side standards *e e* are integrally united by a cross-bar *g*, having flaring and rounded unions *h h*, with the tops of the side standards, as shown in the drawings.

From the top of the supporting-standard *c* is produced a laterally-extended support consisting of spreading arms *i i*, united at their outer and upper ends by a cross-piece *k*, in the center of which is produced a vertical circular sleeve *k'*, as shown in the drawings.

Having thus described my invention, what I claim is—

The design for a supporting standard and frame for churn-operating mechanism, as herein shown and described.

In testimony whereof I have signed my name to this specification in the presence of two subscribing witnesses.

THOMAS FRANCIS TIERNEY.
